FUSE FOR HIGH-EXPLOSIVE SHELLS.

1,169,747.

Specification of Letters Patent.

Patented Jan. 25, 1916.

Application filed October 24, 1914. Serial No. 868,395.

To all whom it may concern:

Be it known that I, HUGO KARL MORÉN, a subject of the King of Sweden, residing at Bofors, Sweden, have invented new and useful Improvements in Fuses for High-Explosive Shells, of which the following is a specification.

As a safety device for shell fuses, especially for high explosive shells, a member 10 has already been employed which normally cuts off the channel for leading the fire from the igniting cap to the bursting charge, but which can be caused to leave said channel free under the influence of the centrifugal 15 force caused by the rotation of the projectile. When it was desired to arrange said fuses so as to be adjustable at will for immediate or retarded explosion, the construction has, however, hitherto been very complicated and thus inconvenient.

The present invention provided a solution of the said question of adjusting fuses of the aforesaid kind, which results in a little complicated construction, and which is founded 25 upon the principle that two fire channels lead from the igniting cap, which channels are controlled by one cutting off member, and one of which leads directly to a secondary igniting device, the other to a retarding device which in its turn ignites the secondary device. The movements of the controlling member then are regulated by a device in such manner, that in arming the fuse either both channels or only the one 30 leading to the retarding device is opened. In the former case, the explosion of course takes place immediately, in the latter case it is retarded.

A form of the invention applied to an 40 impact fuse is illustrated in the accompanying drawing where—

Figures 1 and 2 show the fuse in two different central longitudinal sections, Figs. 3 and 4 cross sections on the lines 3 and 4, respectively, in Fig. 1 in locked (unarmed) position, Fig. 5 a cross section corresponding to Fig. 3 in the position for retarded explosion and Fig. 6 a similar cross section in the position for immediate explosion.

50 *a* is the fuse body proper which is externally threaded for being screwed into the front end of the projectile. At its rear end, it has a narrower, similarly threaded portion on which is screwed a cap *c* filled with 55 an initial charge *d*, while in a recess therein

is screwed a cap *e* containing a detonator charge *f*. In the front end of the fuse, there is screwed a cover *b* carrying the igniting point *b*₁ and closing a central recess *a*₁ in which the hammer *g* and the members 60 controlling its movements, namely, the safety ring *h* and the spring *i*, are adapted to move. In the front portion of the hammer *g*, there is arranged an igniting cap *j*, from which a fire channel *k* leads longitudinally through the hammer.

From the bottom of the recess *a*₁ two axial channels *v*₁ *v*₂ lead rearward in the fuse body where they are intersected by a radial cross channel *u*₂ the outer portion *u*₁ of 70 which is wider than the inner one. The axial channel *v*₂ lying closest to the mouth of the channel *u*₂ continues right through the fuse body to the detonator charge *f*. The other axial channel, on the contrary, is 75 continued by a transverse channel *v*₃ which in its turn is in communication with the charge *f* through a channel *v*₄ filled with a retarding charge, for instance compressed, 80 common powder.

The locking or cut off member *t* is arranged in the transverse channel *u*₂. It is provided with a longitudinal channel *t*₃ and with two cross channels *t*₁, *t*₂ which do not run through but communicate with the longitudinal channel and also—in the innermost position of the cut off member—with the front portions of the fire channels *v*₁, *v*₂ respectively. The cut off member further is provided with a head which coöperates with 90 a special safety pin *m* for controlling the movements of said member.

The safety pin *m* is arranged in an axial channel *l* eccentrically arranged in the fuse body. It is provided with a head having a 95 chamfered portion *m*' on the side facing the pin, as can be seen in Figs. 4-6, and at the other end with a threaded portion *o*' by means of which it is screwed into another pin *o*, a spring *n* being also squeezed between the two members *m* and *o*. The pin *o* can be rotated from outside together with the pin *m*. The spring *n* bears against a sleeve *r* inserted into the channel *l* and retained by means of a screw *s*.

When the fuse is safe (unarmed), its members occupy the positions shown in Figs. 1-4. In firing the gun, the pin *m* slides backward by reason of its inertia, carrying forth the member *o* and the spring 110

n which retains the pin after its displacement. The chamfered portion *m*₁ then is positioned just opposite to the cut off member *t* and according to the position to which 5 the pins *m* and *o* have been previously set by rotation, the position will be that shown in Figs. 5 or 6. By reason of the centrifugal force which then soon occurs by the rotation of the projectile, the cut off member *t* 10 is pressed outward as soon as the strong friction caused by the acceleration of the projectile ceases, and if then the safety pin *m* occupies the position shown in Fig. 5, it will check the member *t* in such position as 15 to leave the channel *v*₁ free but still close the channel *v*₂. On impact, the hammer strikes the igniting point and ignites the cap *j*. The fire then passes through the channels *k* and *v*₁ to the retarding charge in the channel *v*₄ which after a certain space of time 20 carries it farther to the charges *f* and *d*. The explosion thus will be retarded. If, on the contrary, the pin *m* has been rotated to the position shown in Fig. 6, the member *t* 25 can be completely ejected, and the fire then, on impact, is led directly from the igniting cap *j* through the channels *k* and *v*₂ to the charge *f* so that an immediate explosion will occur. If the igniting cap *j* should be 30 unintentionally ignited before the firing of the gun, the fire will rush out through the channels *k*, *t*₁, *t*₂ and *t*₃ without reaching the charge *f*.

Having now particularly described the 35 nature of my invention and the manner of its operation, what I claim is:

1. In shell fuses, an elongated body, a primary igniting charge carried by the body, a bursting charge, said body having a 40 plurality of longitudinal channels forming communication between said charges, a radially displaceable plunger member normally crossing said channels so as to cut off the communication, said plunger member 45 being displaceable in such direction as to open said channels successively when dis-

placed by centrifugal action, and a controlling member serving to arrest the plunger member in successive positions.

2. In shell fuses, an elongated body, a 50 primary igniting charge carried by the body, a bursting charge, said body having two longitudinal channels forming communication between said charges, a radially displaceable plunger member crossing said 55 channels to cut off the communication normally and having a longitudinal channel and two cross channels communicating therewith and normally registering with the end portions of each of said first named 60 channels which communicate with the igniting charge, the plunger being displaceable by centrifugal action to open the communication between charges, and a controlling member normally engaging said plunger so as to prevent its longitudinal displacement.

3. In shell fuses, an elongated body, a primary igniting charge carried by the body, a bursting charge, said body having 70 two longitudinal channels forming communication between said charges, a radially displaceable plunger member crossing said channels and having one longitudinal channel and two cross channels communicating 75 with the longitudinal channel and normally registering with each of said first named channels, and a rotatable and longitudinally displaceable controlling member having different locking surfaces which enable 80 it to check the plunger member either in a position for cutting off both of the first named channels, or in a position for leaving one of said channels free or in a position leaving both channels free.

In testimony whereof I have signed my name to this specification in the presence of two subscribing witnesses.

HUGO KARL MORÉN.
